FIG. 3.

Inventor
George Albert Lyon.

By Charles Marshall Atts.

UNITED STATES PATENT OFFICE

96,327

DESIGN FOR A WHEEL OR SIMILAR ARTICLE

George Albert Lyon, Allenhurst, N. J.

Application December 19, 1934, Serial No. 54,489

Term of patent 14 years

To all whom it may concern:

Be it known that I, George Albert Lyon, a citizen of the United States and residing in the city of Allenhurst, in the county of Monmouth and State of New Jersey, have invented a new, original, and ornamental Design for a Wheel or Similar Article, of which the following is the specification, reference being had to the accompanying drawing, forming a part thereof.

On the drawing:

Figure 1 is an outer side view of a wheel showing my design, which wheel has lustrous metallic disk and hub cap parts encircled by relatively darker rim and hub portions of the wheel the

shading in this figure illustrating contrasting colors.

Figure 2 is a side elevational view of the device shown in Figure 1, partly in section and partly broken away, so as to show the arrangement of the disk with respect to other parts of the wheel.

Figure 3 is a fragmentary profile view showing in outline form the contour of my novel wheel design.

I claim:

The ornamental design for a wheel or similar article as shown and described.

GEORGE ALBERT LYON.
